UNITED STATES PATENT OFFICE.

WILLIAM HAINSWORTH AND RALPH UNDERWOOD, OF JAMESTOWN, NEW YORK.

SHUTTLE-GUARD.

1,182,476.

Specification of Letters Patent.

Patented May 9, 1916.

Application filed January 26, 1916. Serial No. 74,401.

To all whom it may concern:

Be it known that we, WILLIAM HAINSWORTH and RALPH UNDERWOOD, citizens of the United States, residing at the city of 5 Jamestown, in the county of Chautauqua and State of New York, have invented certain new and useful Improvements in Shuttle-Guards, of which the following, taken in connection with the accompanying drawings, is a specification.

The invention relates to looms and is an improvement upon the shuttle guard construction shown in our application for Letters Patent filed April 19th, 1915, Serial 15 No. 22,247; and the object of the improvement is to provide a simpler and stronger construction which is semi-automatic in its action, which more completely guards the operator and is more convenient for the 20 weaver to operate; and the invention consists in the novel features and combinations hereinafter set forth and claimed.

In the drawings, Figure 1 is a perspective view of the hand-rail of the loom with the 25 shuttle guard attached thereto in the open position above the warp threads; and Fig. 2 is a similar view with the shuttle guard in the folded or closed position and the shuttle about to pass into the box. Fig. 3 is an 30 elevation of one of the bracket pieces for attaching to the hand-rail and one of the pivotally mounted supports with a portion of the guard rods and the operating spring connecting said rods, the parts being shown 35 in the closed position with the spring extended. Fig. 4 is a top plan view of a long hand-rail for a loom for weaving wide cloth showing a double section shuttle guard construction, each of said sections folding in 40 opposite directions toward the shuttle box and away from the center of the hand-rail. Fig. 5 is a sectional view at line X X in Fig. 2, of the hand-rail and lay beam of the loom with the warp threads extending there- 45 through and the shuttle in position between the threads. Fig. 6 is a front elevation of one of the brackets and pivotally mounted supports with a portion of the guard rods attached thereto in the open position; and 50 Fig. 7 is a top plan view of the same. Fig. 8 is an elevation of one of the pins or rivets for pivotally attaching the guard rods to the supports.

Like characters of reference refer to corresponding parts in the several views.

The numeral 10 designates the hand-rail and 11 the lay beam or shuttle board of the loom.

The numeral 12 designates the warp threads and the numeral 13 the shuttle and 14 the shuttle boxes.

The shuttle guard comprises a pair of light guard rods 15 which are pivotally attached to the underside of the support pieces 16, which supports are riveted or hinged to 65 the bracket plates 17 by a pin 18, the pin or rivet 18 being formed with a shoulder 19 midway of its length to hold the rods 15 in such a manner as to insure free pivotal movement. The rods 15 are provided with 70 sidewise lugs 20 having a hole 21 therethrough for the rivet 18. This arrangement insures free pivotal action of all the parts and when the bracket plates 17 are attached to the hand-rail, supports the guard rods 15 75 lengthwise of the hand-rail in front of the same over the track of the shuttle.

The bracket 17 is preferably struck from a sheet metal plate with holes 22 therein for attachment to the hand-rail and an outwardly projecting lug 23 to which the support piece 16 is pivotally attached. The outer end of the lug 23 and inner end of the support piece 16 is rounded at one corner 24 and square at the other 25 so as to 80 permit said support 16 to pivotally turn sidewise toward the hand-rail from the round corner 24 and in one direction only, the square corner 25 of the support 16 providing a positive stop against the bracket 85 plate 17 and the square corner of the lug 23 simultaneously striking against the wall of the downward bend 26 in the support piece 16, the support piece 16 being provided with downwardly bent steps to support the rods 15 one below the other to better cover the track of the shuttle 13. This arrangement brings the outer rod 15 fairly close to the warp threads 12, as shown in 90 Fig. 5.

In order that the rods 15 and supports 16 may fold closely against the side of the hand-rail 10, a notch 28 is provided in the outer vertical bend 26 of the support piece 16, which notch 28 receives the upper rod 105 15 when the rods and support pieces 16 are turned sidewise. The friction of the rod 15 in the notches 28 being sufficient to assist in holding the shuttle guard in the folded position. The control of the shuttle guards 110

is largely attained, however, by means of a coil spring 29 which is attached diagonally between the rods 15, the opposite ends of the spring 29 being attached one end to the outer and the other to the inner rod. This arrangement of the spring 29 exerts the full force of said spring to throw the rods 15 to the open or extended position except when said rods are turned to the closed position 10 or flat against the hand-rail 10, in which position the spring 29 while it is given its maximum extension, being straight in line with the rods 15 is on a dead center and does not exert a sidewise pull toward the open 15 position but assists in holding the shuttle guard in the closed position, so that the weaver or operator can easily push the shuttle guard back against the hand-rail 10 and it will stand in that position until manually moved or until the movement of the hand-rail 10 in starting the loom shakes it free when it immediately flies to the open 20 position. This arrangement makes the action of the shuttle guard semi-automatic, 25 that is, it has to be manually placed in the closed position but the starting of the loom with the reciprocal movement of the hand-rail 10 automatically throws the shuttle guard into the extended or guarding position.

When the hand-rail is of any considerable length, as for weaving fabrics above a narrow width, it is preferable to provide a double shuttle guard, that is, two shuttle 35 guards on the hand-rail as shown in Fig. 4, each of said shuttle guards opening toward the center of the rail and closing toward the shuttle boxes or ends of the hand-rail, the positive stops 25 being toward the center of 40 the rail for each of the two shuttle guards since they move in opposite directions. This arrangement provides a positive stop for the shuttle 13 when it flies out of the warp and strikes any portion of the shuttle guard. 45 This usually happens as the shuttle leaves the box 14 and mounts the warp threads 12, being deflected by some lump or knot which turns the course of the shuttle 13, causing it to fly outward or upward.

It is apparent that the semi-automatic action of the shuttle guard by the springs 29 attached to the rods 15 and the arrangement of the positive stops 25 placed in opposite 55 directions in the double guard, gives greatly added protection to the weaver and is of great convenience over our former construction in which the weaver had to operate a latch or lock to release or hold the shuttle guard. The new arrangement of the spring 60 29 attains this object far better and permits

the free semi-automatic action of the shuttle guard.

We claim as new:—

1. A shuttle guard for looms comprising a hand-rail, spaced brackets on said hand-rail, support pieces pivotally attached to said brackets to fold sidewise, spaced rods pivotally attached to said support pieces to fold therewith, and a coil spring attached at its opposite ends to said rods to aid in 70 the operation of said rods.

2. A shuttle guard for looms comprising a hand-rail, spaced brackets on said hand-rail having projecting lugs, support pieces pivotally attached to said lugs to fold side- 75 wise and having a notch in the side thereof, spaced rods pivotally attached to the under- side of said support pieces to fold there- with, one of said rods folding into said notch, a coil spring attached at one end to 80 the inner rod and at the other end to the outer rod at an inclination in the direction to which said shuttle guard is folded, and a positive stop for said shuttle guard against folding in the opposite direction.

3. A shuttle guard for looms comprising a hand-rail, separate parts of said shuttle guard one for each half of said hand-rail each part folding sidewise away from the center of said rail to the folded position 90 and toward the center of said rail to the ex- tended position, and positive stops on each of said parts of said shuttle guard to pre- vent said guards moving beyond said ex- tended position.

4. A shuttle guard for looms comprising the combination with a hand-rail of a two- part guard each having spaced brackets on said hand-rail with projecting lugs, support pieces pivotally attached to said brackets 100 to fold sidewise in one direction only, each of said support pieces of each of said parts folding toward its end of said hand-rail, a positive stop for said support pieces at the extended position, spaced guard rods pivot- 105 ally attached to said support pieces to fold therewith, and a coil spring attached at one end to the inner guard rod and at the other end to the outer guard rod and extending at an angle toward the respective end of said 110 hand-rail toward which it folds to aid in operating the respective parts of said shuttle guard.

In testimony whereof we have affixed our signatures in the presence of two witnesses.

WILLIAM HAINSWORTH.

RALPH UNDERWOOD.
